UNITED STATES PATENT OFFICE.

ELNATHAN M. COBB, OF DUBUQUE, IOWA.

DEVICE FOR OPENING AND CLOSING FURNACE-DOORS.

SPECIFICATION forming part of Letters Patent No. 250,424, dated December 6, 1881.

Application filed April 19, 1881. (No model.)

To all whom it may concern:

Be it known that I, ELNATHAN M. COBB, of Dubuque, in the county of Dubuque and State of Iowa, have invented a new and useful Device for Opening and Closing Furnace-Doors; and I do hereby declare that the following is a full and exact description of the same, reference being had to the accompanying drawings, and to the letters of reference marked thereon.

10 My invention relates to that class of inventions known as "operating-doors," and is especially adapted to be used on the doors of locomotive, marine, or stationary furnaces.

15 The object I have in view is to secure means by which fire-doors of furnaces, &c., can be opened and closed by foot-power, thereby greatly facilitating the fireman in feeding his furnace with fuel, and lessening the injury done the fire and the heated flues of the boiler 20 by the admission of cold drafts of air thereon.

I have discovered, by experience, that a large amount of heat is wasted and cold air admitted on the top of the fire and against the heated flues if the door of the engine or fire-box is 25 allowed to remain open while coal or wood is being secured and supplied to the fire. The most serious matter to be considered is the injury done the flues of the boiler by the change of temperature. To avoid this, firemen, according to the custom now in vogue, are in the 30 habit of opening by hand the door of the furnace, shoveling in all the coal or wood they have convenient, and then closing the door until they can obtain more fuel. To do away 35 with this inconvenience I have conceived the idea of opening the door by means of the foot, at the same time holding the fuel in my hand, and immediately upon supplying the fuel have the door close automatically. This end I accomplish by means of the device and the combinations hereinafter more fully described, and clearly shown in the accompanying drawings, to which reference is made, and in which—

Figure 1 is a perspective view of my device 45 with the door of the furnace closed; Fig. 2, a similar view with the door open; Fig. 3, a perspective view of my hollow tube or quarter-turn piece, which is attached to the hinge-pin; Fig. 4, a view showing the arm which passes 50 around the upper portion of the hollow tube

and up under the latch of the door, by means of which arm the latch is raised and the door pulled open; Fig. 5, a perspective view, showing the tube and arm seen in Figs. 3 and 4 made of one piece; and Fig. 6, a view showing 55 the construction of the rod and rollers by means of which the quarter-turn piece is raised and operated.

Similar letters refer to corresponding parts throughout the several views.

Although my device can be used on any door whatever, for the sake of convenience in the following description reference will be made only to my device as applied to the doors of locomotive-furnaces.

In the accompanying drawings, A represents a furnace; B, the door of the same, and C the deck of the cab. Under the deck C, I place the lever D, which is of the shape shown in Figs. 1 and 2, or of any desired shape, and 70 which has its bearings at the point G. Upon the ends of this lever, and at right angles thereto, are secured, in any desirable manner, the rods E and F. One of these rods—viz., E, which is designed to be used as a foot-lever—75 projects up through a hole made in the deck of the cab near where the fireman stands when supplying fuel to the furnace, and in a convenient position for him to depress it with his foot while in that position. The rod F is secured to the other end of the lever D, and it also projects up through the deck of the cab, but in nearly a vertical line with the hinge-pin H. Transversely through the upper end of this rod F is passed the pin f, on which are 80 placed the small anti-friction rollers h. By depressing the rod E the rod F is raised, and the rollers h are thereby brought in contact with the hollow tube I. This tube I is made of any suitable material, and is of the shape shown 85 in Fig. 3. It is securely attached at its upper end to the hinge-pin H by means of a screw-thread and nut, or in any other desirable manner. Its lower portion is cut away, as shown in drawings, sufficiently to allow the rollers h 90 in passing upwardly into it to slightly raise it and to revolve it exactly a quarter-way around. The upper portion of this tube is so made as to form a shoulder of sufficient width to render the ringed portion of the arm K flush with the 95 100

lower portion of the tube when said arm is passed around and secured to said tube.

The arm K is made of wrought-iron or other suitable material, and has one end made in the shape of a ring, which passes over and is firmly secured to the upper portion of the revolving or quarter-turn piece I. Its other end is curved upwardly, so as to form a right angle with the main portion of the arm, and is designed to pass up under the end of the hinge L' and rest directly under and against the latch M.

In the above I have described the tube I and arm K as made of separate pieces, and joined together suitably. It is evident, however, that I will not depart from the spirit of my invention by casting or working them in one piece, this way, in fact, being perhaps the most desirable. The hinges L L' are fastened to the hinge-pin H and to the door B in the usual manner, and are of ordinary construction, with the exception that L' has its end which is farthest from the hinge-pin bent outwardly sufficiently to form a guide for the arm K.

The manner of operating my device is as follows: Having procured the supply of wood or coal, the fireman places his foot on the rod E, thereby depressing said rod. This action causes the rod F, which is attached to the other end of the lever D, to rise, and brings the rollers h, secured to this rod, in contact with the hollow tube or quarter-turn piece I. This movement forces upwardly the piece I and the arm K attached thereto. The curved end of the arm K is thus brought in contact with the latch M, which it raises, thus unlatching the door. By a continuation of the pressure of the foot on the rod E, the rollers h, attached to the rod

F, are forced up higher, and enter the cut-away portion of the tube I, which causes this tube and the arm K to revolve. This revolution brings the curved end of the arm K in contact with the looped portion of the hinge L', and draws the door open sufficiently to allow fuel to be supplied to the furnace. Having fed the fire, the fireman removes his foot from the rod E, which causes the rod F to fall, thus releasing the tube I, and the weight of the door then causes it to close automatically.

Having thus fully described my invention, what I claim as new therein, and desire to secure by Letters Patent, is—

1. In combination with the door B, the arm K, hinge-pin H, quarter-turn piece I, and rod F, provided with anti-friction rollers h, substantially as and for the purpose set forth. 55

2. In combination with the door B, arm K, hinge L', hinge-pin H, quarter-turn piece I, and rod F, provided with anti-friction rollers h, substantially as and for the purpose set forth. 60

3. The combination, with the door B, with arm K and quarter-turn piece I, of the rod F, provided with anti-friction rollers h, and the lever D, substantially as and for the purpose set forth. 65

4. The combination, with the door B, provided with arm K and quarter-turn piece I, of the rod F, provided with anti-friction rollers h, lever D, and rod E, substantially as and for the purpose set forth. 70

This specification signed and witnessed this 2d day of April, 1881.

ELNATHAN M. CORB.
